United States Patent Office.

WILLIAM J. TERRY, OF WALLA WALLA, WASHINGTON TERRITORY.

Letters Patent No: 65,776, dated June 11, 1867.

IMPROVEMENT IN FASTENINGS FOR NECK-TIES.

The Schedule referred to in these Letters Patent and making part of the same.

TO ALL WHOM IT MAY CONCERN:

Be it known that I, WILLIAM J. TERRY, of Walla Walla, county of Walla Walla, Washington Territory, have invented a new and useful Improvement in Fasteners for Neck-Ties, &c.; and I do hereby declare the following to be a full, clear, and exact description thereof, reference being had to the accompanying drawing, making a part of this specification, in which—

Figure 1 is a plan view in section of so much of my improvement as is necessary to show the manner of attaching the head to the shank, &c.

Figure 2 is a side elevation of my improved fastener.

Figure 3 is a similar view with the head removed.

Figures 4, 5, 6, 7, 8, 9, and 10 show modifications in the construction of the fastener, hereinafter explained; and

Figure 11 represents a cravat or tie provided with an eyelet or perforation through the tie for adapting it to use with my improved fastener.

Similar letters of reference denote corresponding parts in all the figures.

In the employment of the various kinds of neck-ties in use, and with which I am acquainted, great difficulty and consequent vexation have resulted from their liability to get out of order, from the breaking of the elastic or other fastening by which they were secured, the rumpling or creasing of the tie, &c.; and the object of my invention is to provide a neat and simple fastening, one that is durable and not liable to get out of order, and which at the same time is susceptible of being made of any desired pattern, configuration, or degree of ornamentation to suit the taste of the wearer, or adapt it to the kind or style of cravat or other article of dress which it is used to fasten.

My invention consists in the construction of the fastener or stud with a removable head, which, when in use, is connected to the shank by a spring or screw, and which may be readily removed and replaced for the purpose of attaching or detaching the tie or other article of dress secured thereby. It further consists in forming a slot in the fastener, whereby it is adapted, in connection with the removable head, to receive ornaments, such as lockets, arrows, drops, &c., as hereinafter explained; and it further consists in the manner of adapting the tie or other article of apparel to be used in connection with the fastener, by the application thereto of an eyelet hole, either worked therein or metallic, as hereinafter set forth.

To enable others to understand and use my invention, I will describe the same with reference to the drawings, in which—

a represents the shank, and *b* a disk or flange, formed on one end thereof, or applied thereto in any usual manner. *b'* is a second flange, formed upon or secured to the shank at a suitable distance from flange *b* to form, if desired, a stud fastening for the neck band. The shank *a* is made to extend beyond the disk or flange *b'*, where such flange is used, to receive the cravat or tie, which is provided with an eyelet hole or perforation to adapt it to receive the shank. Said shank has a groove formed in its extended end to receive the spring-catch *c* in the detachable head *c*, (see figs. 1, 2, 3,) or instead of the groove and spring-catch, a screw-thread may be cut on the end of the shank, and the head may be made to screw thereon in the manner shown by the drawings, figs. 4, 5, 6, and 10, serving thereby to properly compress and secure the tie or other article fastened against the disk or flange *b'*. Where the screw is used, the shank may be slotted to receive an arrow or other ornamental device, as shown in the drawings, figs. 4, 5, and 6, between the head and the tie secured upon the shank thereby. In figs. 7 and 8 the shank is shown perforated to receive a locket or other form of ornament, and in figs. 9 and 10 the head is applied by screwing it upon the shank, as before explained, and has attached to it a small ball or knob, which may, if desired, be provided with a shank, and made to screw into the head in such manner as to form a means of attaching a drop, pin, or other desired device, as shown by the drawing. The tie or other article of dress to be secured is provided with a perforation or eyelet, *f*, applied in any usual manner to adapt it to receive and be secured upon the shank, as explained.

The operation will be readily understood: Where the fastener is used for securing the cravat, and is provided with both flanges *b* *b'*, it may be inserted through perforations made in the neck-band of the shirt, the same as the ordinary stud-fastening. The perforated ends of the collar and the cravat are then slipped over

the extended end of the shank, when the head is secured thereon in the manner explained, and forms an effectual fastening for the collar and tie. The flange b' may be dispensed with if preferred, when the shank is simply passed through the several articles from the inside, which are then compressed against flange b and held by the head c . The head c and flanges or disks may, if desired, be provided with small sharp points, which penetrate the tie or other articles of dress secured, and thereby prevent the fastener from turning. The fastener may be made of any suitable material, such as iron, steel, brass, or the more valuable metals; and pearl, ivory, vulcanized rubber, or even wood may be used if desired, and, as will be seen from the drawing, any desired configuration may be given to the head or clasp c , to adapt it to the particular taste or fancy of the wearer.

Having now described my invention, what I claim, and desire to secure by Letters Patent, is—

1. The stud or fastener, provided with the removable head, constructed and applied substantially as and for the purpose set forth.
2. The slotted shank, in combination with the removable head, substantially as and for the purpose described.
3. The head c and flanges or disks b b' , provided with points for the purpose of preventing the turning of the fastener, as described.
4. The neck-tie, provided with the eyelet-hole f , whereby it is adapted to be used in connection with the fastener, substantially as described.

In testimony whereof I have hereunto set my hand this twenty-fifth day of May, 1867.

WILLIAM J. TERRY.
